UNITED STATES PATENT OFFICE.

WILLIAM T. HENRY, OF HOUSTON, TEXAS.

GARMENT HANGER.

Application filed April 28, 1925. Serial No. 26,387.

This invention relates to new and useful improvements in a garment hanger.

One object of the invention is to provide a garment hanger specially designed for the purpose of hanging trousers in such a manner as to maintain the leg creases therein and to prevent the same becoming misshapen or wrinkled. The hanger also includes means for hanging the coat thereon so as to preserve the proper shape thereof.

Another object of the invention resides in the provision of a garment hanger which may be folded, either with, or without the trousers clamped therein, so that the hanger alone, or with the trousers therein, may be packed in a suit case, trunk or the like, and will occupy small space therein.

With the above and other objects in view this invention has particular relation to certain novel features of construction, operation and arrangement of parts, an example of which is given in this specification and illustrated in the accompanying drawings, wherein:—

25 Figure 1 shows a fragmentary rear view of the hanger.

Figure 2 shows a transverse sectional view taken on the line 2—2 of Figure 1.

30 Figure 3 shows a bottom end view of one side of the hanger.

Figure 4 shows a fragmentary side view thereof.

35 Figures 5 and 6 show side and end views respectively, of one side of the hanger, as partially folded, without the trousers clamped therein.

Figures 7 and 8 show side and end views, respectively, of one side of the hanger, as folded, and

40 Figure 9 shows a sectional view thereof, taken on the line 9—9 of Figure 1.

Referring now more particularly to the drawings, wherein like numerals of reference, designate similar parts in each of the figures, the numerals 1, 1' designate oppositely disposed end clamps, designed to clamp the bottom ends of both trouser legs between them. These clamps have their mid sections outwardly curved as at 2, 2 to provide space for the bulky side seams of the trouser legs. These clamps are mounted on the wire frames 3, 3, of looped formation, and having the upturned ends 4, 4, which are pivoted on the pintle 5. A suspending hook 6 is pivoted on said pintle between said

arms 4. The lower margin of the clamp 1' is upturned on each side of the curved portion 2, said upturned parts being toothed, forming the ratchets 7, 7.

Leg clamps for the front and rear of each 69 trouser leg, have been provided and designated as a whole by the numerals 8 and 9. These clamps may be suspended from said ratchets by means of the hooks 10, 10 which are formed to engage over said upturned 65 portions and with the ratchet teeth thereof. When the clamps 8 and 9 are applied to the trouser legs, as hereinafter explained, the hooks 10, 10 may be spread apart, to stretch the material of the garment so as to remove 70 all wrinkles and then engaged with the ratchet teeth to hold them in the required position.

The lower ends of the leg clamps are held the required distance apart by means of the 75 brace arms 11, 12 which are pivoted at their outer ends to the respective clamps 8 and 9.

The other ends of these arms telescope, the arm 12 telescoping into the arm 11, and this latter arm has a yieldable detent 13, adapted 80 to engage into one of a row of perforations 14 in the arm 12, thus permitting the adjustment of said arms, so that when the clamps are secured to the trouser legs they may be spread so as to stretch the material of the 85 legs to remove the wrinkles.

Each clamp 8 and 9 is formed with the side plates or leaves 15, 15 and the intermediate plate or leaf 16, all hinged together, at one edge, by the hinges 17, 17. These side plates, 90 and intermediate plate, or leaves, may be opened to receive the front and rear folds or creases, of the legs, 18, 18, the leaf 16 being inserted between the legs and the side leaves clamping them on opposite sides, as illustrated 95 in Figure 3. These clamps are held in clamping position by means of the upper, lower and intermediate spring clips 19, which are slipped thereover, as shown.

The leaves 15 are sectional, being preferably of two sections, which are hinged together by the hinges 20, 20.

If it be desired to fold the hanger, while the trousers are clamped therein the corresponding pintles 21, 21, of the hinges 20, may be 105 removed and the hanger and garment folded as shown in Figures 7 and 8.

If it be desired to fold the hanger without the garment therein the clamps 8 and 9 may be opened on the hinges 17 and brought to a 110

common plane, with the leaf 16 lying adjacent either leaf 15, and the clamps then folded on the hinges 20. It is to be noted that the intermediate leaves 16, of each clamp 5 8 are cut on the line of the hinges 20 to permit this folding.

The end clamps 1, 1' are held in clamping position by means of the oblong rings 22, 22, which fit around and slip on the upper sides 10 of the loops of the frame members 3.

For the purpose of providing a coat hanger, there are provided the shoulder supports 23, 23. The inner ends of these supports are formed with sleeves 24, 24 which form 15 slideable bearings on the upper sides of the rear frame member 3 on opposite sides of the hanger. It is obvious that these shoulder supports may be pulled out, or extended to 20 form a coat support, or moved inwardly when it is desired to fold, or collapse the hanger. The hook 6 may also be folded over and the entire device, with or without a garment therein, folded into small space.

What I claim is:—

25 1. A clothes hanger including end clamps, hinged together, and adapted to clamp the ends of trouser legs, ratchet members carried by one of said clamps, side clamps, depending from one of the end clamps and adapted to 30 receive front and rear folds of said legs between them, hooks carried by the side clamps adapted to engage with the respective ratchet members, said side clamps being adjustable toward and from each other, on said supporting end clamp.

2. A clothes hanger including end clamps hinged together and adapted to clamp the ends of trouser legs, side clamps, depending from one of the end clamps and adapted to

receive front and rear folds of said legs between them each side clamp being formed of side leaves and an intermediate leaf, all hinged together, said side leaves being formed of sections hinged together, and the intermediate leaves being formed of sections separated on the line of hinges uniting the side sections. 45

3. A clothes hanger including end clamps hinged together and adapted to clamp the ends of trouser legs between them, side 50 clamps depending beneath the end clamps and adapted to clamp front and rear folds of said legs between them, said side clamps being adjustable on the supporting clamp, adjustable means for spacing said clamps 55 apart, each side clamp being formed of side leaves and an intermediate leaf all hinged together, said side leaves being formed of sections hinged together and the intermediate leaves being formed of sections separated on 60 the line of the hinges uniting the side sections.

4. A clothes hanger including oppositely disposed end clamps, wire frames of looped formation on which said clamps are mounted, said frames having upturned ends, a pintle 65 on which said upturned ends are mounted, a suspending hook pivoted on said pintle between said arms, upturned ratchets carried by one of said clamps and spaced apart, side 70 clamps, hooks carried by the upper ends of said side clamps and engaging with the respective ratchets and adjustable means for securing said side clamps a selected distance apart.

In testimony whereof I have signed my 75 name to this specification.

WILLIAM T. HENRY.
